BRAKE BEAM

Frederic Schaefer, Pittsburgh, Pa.

Application August 3, 1938, Serial No. 222,828

9 Claims. (Cl. 188—226)

This invention relates to railway brake beams, and more particularly to truss type beams.

As a factor in making railway rolling stock lighter it is desirable to decrease the weight of 5 brake beams, but heretofore no practical way of doing it without unduly weakening the beam has been found. Another of the disadvantages of brake beams today is the loose fit between the 10 brake heads and compression member which occurs after a brief period of service. This is chiefly due to the clearance that is necessary to insure that the compression members will fit in the deep sockets of the brake heads, and to the 15 irregularities in the adjoining surfaces whereby the heads are permitted to rock on the ends of the compression member. Furthermore, the ends of the compression member are sheared, frequently on a slight bias, which often leaves them with fins or rough edges, and the socket in the 20 head is also likely to be covered with scale or a sandy film. As the entire brake beam structure is generally held together only by nuts at the ends of the tension member and by rivets or a key connecting the strut to the compression member, it 25 has not been possible to hold the component parts rigidly together.

The bearing area between the strut and tension member is quite small, whereby the strut sometimes cuts into the tension member. Due to the 30 diameter of the threaded ends of the tension member at the root of the threads being less than the diameter of the rest of the member, the cross-sectional area of the ends is materially decreased whereby the tension member occasionally breaks 35 at the root of the threads. This danger is increased when the nut does not sit squarely against its supporting surface on the adjoining brake head, and thereby exerts a bending strain on the end of the tension member.

It is among the objects of this invention to 40 provide a relatively light weight brake beam without sacrifice of strength, a more permanently rigid brake beam, and a longer-life beam.

In accordance with this invention a brake beam 45 is formed of a compression member having spaced top and bottom walls joined by a side wall between which one end of a strut has a wedge fit. The other end of the strut is provided with a 50 large bearing area for the tension member so that the strut will not cut into it. The compression member is made substantially C-shape in cross section from relatively thin material and is strengthened by thickening its edge portions and also, preferably, spaced portions of its back 55 wall. Carried by the ends of the compression

member are brake heads each of which has a laterally projecting tongue that extends into the adjoining end of the compression member in which it is tightly wedged in place by engagement with the inner surface thereof. For this 5 purpose each end of the compression member preferably diverges, and the tongue is tapered so that it will have a wedge fit with the diverging walls. At the base of the tongue the head is provided with a shallow lateral recess for tightly receiving the end of the compression member. The inner surface of the nut that is threaded on each 10 end of the tension member is convex and is seated in a concave socket in the adjoining brake head so that it aligns itself with the force exerted 15 upon it. The threaded end of the tension member is strengthened by increasing its diameter before threading so that its diameter at the root of its threads is substantially the same as the 20 diameter of the rest of the tension member.

The preferred embodiment of the invention is 25 illustrated in the accompanying drawings in which Fig. 1 is a fragmentary plan view of my brake beam; Fig. 2 is a fragmentary side view of one end of the compression member and head; Fig. 3 is a side view of the strut; Fig. 4 is an enlarged end view of the beam showing a brake head applying a shoe to a wheel; Fig. 5 is an enlarged 30 plan view of the brake head; Fig. 6 is a vertical section of the head taken on the line VI—VI of Fig. 1; Fig. 7 is a vertical section of the compression member taken on the line VII—VII of Fig. 1; Fig. 8 is an enlarged longitudinal section through 35 the brake head taken on the line VIII—VIII of Fig. 1; and Fig. 9 is an enlarged side view of a threaded end of the tension member and the nut that is threaded onto it.

Referring to Fig. 1 of the drawings, a truss type 40 brake beam is formed from a compression member 1 which carries at each end a brake head 2 to which the ends of a tension member 3 are connected. The central portion of the tension member is spaced from the cambered compression member in the usual manner by a strut 4. This general construction of the beam is the same 45 as standard beams now in use, my invention having to do with improvements in the component parts of the beam and in the way in which they are connected together. Thus, as shown in Fig. 7, the compression member has spaced top and 50 bottom walls 6 joined by an integral side or back wall 7, and is preferably generally U- or C-shape in cross section. The compression member is made from a rolled section which is most suitably a .40-.50 carbon steel because of its higher 55

elastic ratio. The weight of this member is decreased by making it from relatively thin stock, but its strength and resistance to deflections are not also decreased because it is reinforced in the 5 areas where the greatest effect is obtained. In other words, the slenderness ratio of this compression member is much greater than that figured for present types of beams because the neutral axis or center of gravity of the compression member is located farther from its back wall 10 than is the usual case. This is accomplished by thickening the spaced longitudinal edges 8 of the compression member along their inner surfaces. This thickening also reinforces the edges 15 against bending in any direction. The compression member is also strengthened, without adding materially to its weight, by providing the inner surface of its back wall with vertically spaced raised portions that form interior longitudinal 20 ribs 9.

Another feature of this invention is that the 25 brake heads 2 are so connected to the ends of the compression member that the connection remains rigid indefinitely. Accordingly, each brake head, instead of being provided with the usual socket 30 for receiving an end portion of the compression member, is provided with a laterally projecting tongue 11 (Fig. 5) that extends into the adjoining end of the compression member and frictionally engages its inner surfaces.

Preferably, as shown in Figs. 1 and 8, the end 35 portions of the compression member walls diverge toward the ends of the member, and the brake head tongue tapers or converges toward its free 40 end at substantially the same angle. The outer surface of the tongue conforms in contour to the adjoining inner surface of the compression member (Fig. 7), and these two members are of such size as to require the tongue to be driven into the 45 compression member whereby a wedge fit is provided. To further rigidly secure the head and compression member together, the head is provided with a shallow recess 12 at the base of the tongue for receiving the end of the compression 50 member which is thereby wedged in the recess between its inner and outer walls (Figs. 5, 6 and 8). To insure engagement of as much area as possible of the adjoining surfaces of the compression member and tongue, the end portions of the 55 compression member are tapered or coned in a heading machine and their end walls are squared for bearing flat against the heads. The recess 12 in each head is preferably shaped with a hard baked core to assure a true and flat bearing surface, and as the recess is shallow it can be readily cleaned of sand and scale. Due to the cross-sectional C-shape of the compression member, the brake head tongue is prevented from being forced out of the member through the space between its edges 8 (Fig. 7).

Each brake head is provided with the usual opening 15 through which one end of tension member 3 extends. It is another feature of this invention that the nuts 16 that are threaded on the projecting ends of the tension member always seat properly against the brake head. Accordingly, the inner or bearing surface of each nut is convex, as shown in Fig. 9, and forms a portion of a sphere. This surface will hereinafter 65 be referred to as spherical, although it is not a complete sphere. Likewise, as shown in Fig. 5, the surface 17 of the brake head against which this nut bears is concave to form a spherical seat for the nut which therefore can have universal movement thereon. This construction 75

permits the nuts to seat flat against the heads without lateral strain on the end portions of the tension member, regardless of factors that might otherwise prevent proper seating of the nuts. In addition, as the beam deflects under load, the 5 tension rod nut and head assembly is self-aligning to take care of whatever change may take place in their relation.

To avoid fracture of the tension member at the root of its threads, heretofore due to a smaller 10 cross-sectional area at that point, its end portions 18 are upset before threading by an amount preferably at least as great as the depth of the threads. Consequently, when these enlarged end portions are threaded, the roots of the threads 15 are substantially in line with the outer surface of the remainder of the rod. In other words, the diameter of the tension member at the roots of the threads is substantially the same as the diameter of the rest of the rod, as shown in Fig. 9. 20 The weight of the tension rod can be reduced by using a smaller rod of a material highly resistant to stretching, and upsetting the ends in the manner just mentioned for receiving standard size 25 nuts.

The end of strut 4 which engages the tension member is provided with lateral extensions 21 (Fig. 1) that add materially to the length of the seat for the tension member to prevent the strut from cutting into the tension member. As shown 30 in Figs. 1 and 3, the other end of the strut is provided with laterally projecting lugs 22 which are so shaped as to conform to the inner surface of the compression member behind thickened edges 8. The strut can therefore be connected 35 to the compression member only by inserting it therein from one end of the member. Lugs 22 are slightly wider than the space between the top and bottom walls of the compression member so that the strut has to be driven into the 40 member, thereby providing a wedge fit between them which helps rigidify the entire brake beam. The strut is further held in place by the usual rivets 23 extending through lugs 22 and the back wall of the compression member. The strut's 45 bearing area for the inclined brake lever (not shown) is materially increased as shown at 24 in Figs. 1 and 3. In this respect the strut is the same as that shown in my copending patent application Serial No. 161,397, filed August 28, 1937 50 which matured into Patent No. 2,132,222 on October 4, 1938.

According to the provisions of the patent statutes, I have explained the principle and construction of my invention, and have illustrated 55 and described what I now consider to be its best embodiment. However, I desire to have it understood that, within the scope of the appended claims, the invention may be practiced otherwise than as specifically illustrated and described. 60

I claim:

1. A brake beam comprising a compression member having spaced top and bottom walls joined by a side wall, the inner surfaces of the end portions of said walls diverging toward their 65 ends, and a brake head carried by each end of said member, each head being provided with a laterally projecting tongue extending into the adjoining end of the compression member, and the outer surface of said tongue converging toward its inner end with said wall and tongue surfaces engaging each other with a wedge fit.

2. A brake beam comprising a compression member having spaced top and bottom walls joined by a side wall, the inner surfaces of the 75

end portions of said walls diverging toward their ends, and a brake head carried by each end of said member, each head being provided with a laterally projecting tongue extending into the adjoining end of the compression member, and the outer surface of said tongue converging toward its inner end and conforming in contour to said diverging wall surfaces whereby said wall and tongue surfaces frictionally engage each other with a wedge fit.

3. A brake beam comprising a compression member having spaced top and bottom walls joined by a side wall, the inner surfaces of the end portions of said walls diverging toward their ends, and a brake head carried by each end of said member, each head being provided with a laterally projecting tongue extending into the adjoining end of the compression member, the outer surface of said tongue converging toward its inner end with said wall and tongue surfaces engaging each other with a wedge fit, and each head having a lateral recess at the base of its tongue for tightly receiving the end of the compression member.

4. A brake beam comprising a compression member having spaced top and bottom walls joined by a side wall, and a brake head carried by each end of said member, each head being provided with a laterally projecting tongue extending into the adjoining end of the compression member and engaging said walls, a tension member connected to the brake heads, and a strut spacing said members apart, one end of the strut being tightly wedged between the top and bottom walls of the compression member.

5. A brake beam comprising a compression member having spaced top and bottom walls joined by a side wall, and a brake head carried by each end of said member, a tension member connected to the brake heads, and a strut spacing said members apart, one end of the strut

being tightly wedged between the top and bottom walls of the compression member.

6. A brake beam comprising a compression member having spaced top and bottom walls joined by a side wall, and a brake head carried by each end of said member, a tension member connected to the brake heads, and a strut spacing said members apart, one end of the strut being tightly wedged between the top and bottom walls of the compression member and the opposite end of the strut having a relatively long bearing surface for the tension member, said surface having a semi-circular portion in cross section engaging the tension member.

7. A brake beam comprising a compression member substantially C-shape in cross section and having materially thickened longitudinal edges, and a brake head carried by each end of said member, each head being provided with a laterally projecting tongue extending into the adjoining end of the compression member and tightly engaging its inner surface.

8. A brake beam comprising a compression member substantially C-shape in cross section, the longitudinal edge portions of said member being thickened interiorly and the innermost surface of the member being provided with spaced raised portions forming interior longitudinal ribs.

9. A brake beam comprising a compression member substantially C-shape in cross section, the longitudinal edge portions of said member being thickened interiorly and the innermost surface of the member being provided with spaced raised portions forming interior longitudinal ribs, and a brake head carried by each end of said member, each head being provided with a laterally projecting tongue extending into the adjoining end of the compression member and tightly engaging its inner surface.

FREDERIC SCHAEFER.
